(57) **CLAIM**

The ornamental design for an ionized air gun, as shown and described.

DESCRIPTION

The patent or application file contains at least one drawing executed in color. Copies of this patent or patent application publication with color drawing(s) will be provided by the Office upon request and payment of the necessary fee.

FIG. 1 is a left side view of the ionized air gun of the present invention;

FIG. 2 is a right side view thereof;

FIG. 3 is a top view thereof;

FIG. 4 is a bottom view thereof;

FIG. 5 is a rear view thereof; and,

FIG. 6 is a front view thereof.

The drawing is lined for color.

The label in FIGS. 1, 2 and 4 and the letter indicia in FIGS. 1 and 2 forming part of the claimed design is a registered trademark of Static Solutions Ltd.
